L. A. WERNERY.
TYPE WRITING MACHINE.
APPLICATION FILED JAN. 4, 1917.

Patented Aug. 13, 1918.

UNITED STATES PATENT OFFICE.

LESTER A. WERNERY, OF BROOKLYN, NEW YORK, ASSIGNOR TO UNDERWOOD TYPE-WRITER COMPANY, OF NEW YORK, N. Y., A CORPORATION OF DELAWARE.

TYPE-WRITING MACHINE.

1,275,637.

Specification of Letters Patent. Patented Aug. 13, 1918.

Application filed January 4, 1917. Serial No. 140,512.

To all whom it may concern:

Be it known that I, LESTER A. WERNERY, a citizen of the United States, residing in Brooklyn borough, in the county of Kings, city and State of New York, have invented 5 certain new and useful Improvements in Type-Writing Machines, of which the following is a specification.

My invention relates to bookkeeping 10 equipments, a species of loose-leaf bookkeeping sheets being employed with specially designed typewriting machine attachments. Borders, tabs or extensions upon the sheet are adapted to coöperate with alining or 15 positioning devices associated with the typewriter platen, to render the sheet self-positioning at different desired heights. The typist may position a work-sheet accurately 20 on the platen without the necessity of looking at any scale, by passing the sheet around the platen until it is arrested by the positioning device and properly alined by that, with the aid of other devices, if necessary. The ordinary Underwood typewriting 25 machine may be used, and gages or pins may be provided for arresting the work-sheet by means of its shoulders, these gages being separated, to permit the body of the sheet to pass between them. These pins may advantageously 30 be connected to the feed-roll release mechanism, in such a way that the pins are effective when the feed rolls are released, thus making it easy to adjust the paper accurately, while the throwing of the feed 35 rolls against the platen is accompanied by the return of the pins to ineffective position.

A single fixed tab or shoulder may be provided upon opposite sides of the statements, which usually are only once inserted in the 40 machine; while the ledger sheets, which are put into the machine every time a new statement is made out, are to be positioned differently, according to where the last entry thereon ended. These ledger sheets I provide 45 with a detachable border on each side, consisting of a series of detachable segments or tabs, at intervals corresponding to the printed lines thereon. These tabs may be in the form of integral extensions of the ledger 50 sheet, but perforated to make each tab of the above-described size, so that they may be readily detached therefrom. The tabs or segments on one side match those upon the other side. In a loose-leaf ledger system, 55 these tabs may advantageously be on only

one side of the sheet, that is, the side of the sheet which is clamped in the loose-leaf binder, while the sheet itself may be trued or alined with the help of side gages, thus rendering it unnecessary, in many instances, 60 to provide tabs on both sides of the ledger sheet, although in many other instances this will be found advisable.

Other features and advantages will hereinafter appear. 65

In the accompanying drawings,

Figure 1 is a perspective view of a typewriting machine showing so much of the typewriter as needs to be modified, for the purpose of utilizing a simple form of my invention. 70

Fig. 2 is a fragment of a statement sheet showing the shoulder thereon.

Fig. 3 is a side view of the part shown in Fig. 1, the feed rolls thrown off from the 75 platen and the alining pins in collating position.

Fig. 4 is a view similar to Fig. 3, but showing the feed rolls against the platen, the alining pins in their ineffective position, 80 and the type-bar in the act of printing.

Fig. 5 is a fragment of a ledger sheet showing the tabs.

Fig. 6 is a diagrammatic perspective view showing how the sheets may be arranged 85 on the platen.

Fig. 7 is a sectional side view showing the connections between the alining pins and the paper guide.

Fig. 8 is a fragment of another form of 90 ledger sheet.

Fig. 9 is a perspective view showing the paper guide and the sleeve to which it is connected.

The usual Underwood typewriter carriage 95 includes a frame 1, in which is revolvably mounted a platen 2 which is provided with knobs 3, by which it may be turned and also with the usual line-space mechanism including the line-space wheel 4, which is adapted to turn the platen in line-space units when driven by the pawl 5, which is operated in the usual manner by the line-space lever 6. To insert a work-sheet in the platen, the work-sheet is passed over a paper 100 table 7, at the rear of the platen, which curves beneath the platen so as to guide the work-sheet out in front of the platen, carrying it past the front and rear feed rolls 8 and 9. These feed rolls normally bear 105 110

against the platen in order to cause the platen by its revolution to carry the work-sheets forward as it turns, by holding said work-sheets against the platen. The carriage is provided with the usual feed-roll release handle 10, which when depressed from the position seen in Fig. 4 into that seen in Fig. 3, removes the feed rolls 8 and 9 from the platen, thus allowing free passage for the work-sheets. The statement work-sheet is provided with a shoulder 11 which is adapted to strike and be arrested by a left-hand gage or pin 12, said pin being mounted on a transversely extending rock shaft 13, which extends across the carriage above the platen and is journaled in brackets 14 fast to the platen frame. There is usually also provided a second right hand gage or pin 15 which is similarly fast on the rock shaft 13. When the feed rolls 8 and 9 are cast off in the usual manner by operating the finger piece 10, the rock shaft 13 may bring the pins 12 and 15 forwardly so that they stand out nearly horizontal (Fig. 3) from the face of a table 16 upon which the paper is guided, said table extending down some distance toward the printing line and about into contact with the platen. A work-sheet may then be inserted over the usual paper table 7, and between the usual side guides 17 and 18, which serve to start it correctly, and then the work-sheet passes up past the rolls 8 and 9, in front of the platen, onto the table 16. It is guided against the table 16 by fingers 19 and 20 which are fast to said table and extend down to the printing point and slightly in front of the lower paper apron 21 which forms an extension of the paper table 7.

The table 16 with its fingers 19 and 20 may be formed (Fig. 9) integral with a sleeve 22 which extends across between the brackets 14, to which it is fast, and surrounds the rock shaft 13. The rock shaft 13 is connected to the finger piece 10 by means of a rock arm 23, which is fast on the shaft, and pivotally connected by means of a link 24 to the finger piece 10. The sleeve 22 is slotted at 25 to accommodate each of the alining pins 12 and 15.

The fingers 19 and 20, as stated, are rigid with the paper table 16 and rise from collars 26 embracing the sleeve 22, and have faces 27 projecting radially of the platen along the side edges of the paper table 16. The faces 27 are only a little more than sufficient in depth to accommodate the greatest number of work-sheets which is likely to be inserted in the machine. The fingers 19 and 20 are bent so that the flat extensions thereof overlie the face of the paper table 16, and are spaced therefrom sufficiently to accommodate the work-sheets. The lower ends 28 of the fingers 19 and 20 are bent out slightly so as to safely guide

any work-sheet behind the fingers 20 and 19 as it passes upward from the paper apron 21.

In inserting or collating the work-sheets for bookkeeping, there is inserted usually a ledger sheet, to form the inner or bottom sheet, then a carbon sheet, then, if desired, some sheet for keeping a duplicate record, and on top of this is inserted a statement sheet. These sheets are usually assembled with interleaved carbon sheets, and may be either inserted one by one as just stated, or first collated and put into the machine together. Each of these sheets is provided with a shoulder, on each side, to make the sheet self-positioning, the shoulders being adapted to bring the right printed line to the printing point when those shoulders strike the pins 12 and 15 which are in effective position. Since each statement sheet is usually put into the machine only once, it may be provided with a single permanent shoulder 11, for coöperation with the pin 12, the side alinement of this sheet being secured by placing its edge against one or both side guides 17 and 18. Usually it is desirable for the sheet to be provided with two shoulders for coöperation with both pins 12 and 15. The shoulder 11 may be on a detachable margin 29, which is separable from the main sheet or the statement by ripping it along a perforation 30. There may be such a perforation or shoulder on each side of the statement sheet.

The ledger sheet is provided with a series of detachable segments, tabs or shoulders 31, each individually separable by a line of vertical perforations 30 and of horizontal perforations 32. If only one set of shoulders is used on the ledger sheet, and if the ledger sheet is to be bound in the loose-leaf binder by means of a post which passes through circular openings 34 in the ledger sheet at the side thereof, the shoulders 31 may be provided on the side of the sheet which is to lie within such binder, thus presenting a smooth edge of the sheet in handling the bound book. Since a ledger sheet often has quite a margin at the heading, the top shoulders may be separated by differently spaced perforations, as is indicated in Fig. 8, thus serving to minimize the attention needed in utilizing this equipment, because the number of perforations to be detached in first making an entry need not be counted on a sheet like that shown in Fig. 8.

In the assembled diagrammatic perspective view of the collated sheets, Fig. 6, the statement 35 is shown in front, next to this and behind it is a carbon sheet 36, behind that is collated the duplicate sheet 37, behind that is the second carbon 36, and behind that is collated the ledger sheet 33, and the fingers of the operative are shown in the act of grasping and bringing the statement sheet up to proper alinement 130

against the pins 12 and 15 against which the other sheets 33 and 37 have already been alined or collated upon the table 16. In collating each sheet, the operative may, however, slide it along upon the collating table or guide 16 in a manner well known in this art, and while holding it in final position he may slide another sheet up upon the first, and so on, the table 16 supporting the pressure of the fingers upon each sheet as it is lightly slid upon the last, and the tendency being so hold each previously collated sheet up to the gages.

Variations may be resorted to within the scope of the invention, and portions of the improvements may be used without others.

Having thus described my invention, I claim:

1. In a bookkeeping equipment, the combination with a typewriting machine, having alining pins shiftable to ineffective position, of a work-sheet having perforations so as to form a removable shoulder adapted to be positioned against said pins, when portions of the sheet are removed along said perforations.

2. In a bookkeeping equipment, the combination with a typewriting machine, having alining pins shiftable to ineffective position, of work-sheets having shoulders adapted to be positioned against said pins, certain of said work-sheets being perforated so that said shoulders may be detachable to form new shoulders to position said work-sheets against said pins.

3. In a bookkeeping equipment, the combination with a typewriting machine, having alining pins shiftable to ineffective position, of work-sheets of various types having shoulders adapted to be positioned against said pins, to aline said sheets simultaneously, said shoulder on at least one sheet being formed as part of a detachable perforated extension of said sheet.

4. In a typewriting machine, the combination with a rotatable platen and a paper guide adapted to receive paper which has been passed already around said platen, of feed rolls adapted to be cast off from said platen, alining pins adjacent the ends of said paper guide, a shaft on which said alining pins are mounted, to project them substantially vertically from the surface of said guide or rotate them backwardly beneath its surface, a sleeve supporting said guide and surrounding said shaft, paper fingers extending downwardly and rearwardly from said guide, and a paper apron extending up to said fingers and adapted to deliver the leading edge of a work-sheet to said fingers.

5. In a typewriting machine, the combination with a rotatable platen and a paper guide adapted to receive paper which has been passed already around said platen, of

feed rolls adapted to be cast off from said platen, alining pins adjacent the ends of said paper guide, a shaft on which said alining pins are mounted to project them substantially vertically from the surface of said guide or rotate them backwardly beneath its surface, a sleeve supporting said guide and surrounding said shaft, and projections from said paper guide forming edge guides therefor, and continued and extended to form 75 overlying guide fingers therefor.

6. In a typewriting machine, the combination of a revoluble platen and a paper guide adapted to receive a work-sheet which has been already passed part way around the platen, of fingers extending above the surface of said guide to hold a work-sheet thereagainst, removable pins adapted to lie across the channel between said fingers and said guide, and feed rolls normally lying 85 against the platen, but adapted to be thrown off therefrom and when so thrown off moving said pins to ineffective position.

7. In a typewriting machine, the combination of a revoluble platen and a paper 90 guide adapted to receive a work-sheet which has been already passed part way around the platen, of fingers extending above the surface of said guide to hold a work-sheet thereagainst, removable pins adapted to lie 95 across the channel between said fingers and said guide, feed rolls normally lying against the platen, but adapted to be thrown off therefrom and when so thrown off moving said pins to ineffective position, a paper 100 apron extending beneath said platen, and fingers extending downwardly from said guide and bent downwardly to receive the leading edge of a work-sheet from said apron.

8. In a typewriting machine, the combination with a rotatable platen and a paper guide adapted to receive paper which has been passed already around said platen toward the front thereof, of alining pins adjacent the front ends of said paper guide, a shaft on which said alining pins are mounted, to rotate them into a position in the path of paper passing along said guide, or rotate them backwardly out of the path of the 110 paper, and a sleeve supporting said guide and surrounding said shaft.

9. A collating equipment for a typewriting machine having gaging or position-determining devices, said devices spaced apart 120 to form a passage for the portion of the sheets to be collated, said equipment including sheets, some of which have waste strips at each edge thereof, extending beyond the main portion and prepared for severance at 125 various places to form jogs or shoulders for cooperation with said gaging or position-determining devices, so that the main portion of any sheet may pass between said devices, and whereby different sheets may be 130

10. In a typewriting machine, the combination with a rotatable platen and paper-apron therefor, of collating pins or devices at the front side of the platen, and guides for the sheets to be collated, said guides so formed as to guide the paper from the paper-apron to said collating pins or devices.
11. In a typewriting machine, the combination with a rotatable platen and paper-apron therefor, of collating pins or devices at the front side of the platen, a collating table adjacent said pins or devices, and guides for the sheets of paper to be collated, said guides being so formed as to guide the sheets from the paper-apron over the surface of said paper-table to said pins or devices.
12. In a typewriting machine, the combination with a rotatable platen and paper-apron therefor, of collating pins or devices at the front side of the platen, and guiding fingers for the edges of the sheets to be collated, said fingers forming a covered guideway for the sheets as they leave the paper-apron, and serving to guide said sheets to a position adjacent said collating pins or devices.
13. In a typewriting machine, the combination with a rotatable platen and paper-apron therefor, of collating pins or devices at the front side of the platen, and guiding fingers for the edges of the sheets to be collated, said fingers terminating adjacent said paper-apron, and forming a covered guideway for said sheets, so as to positively guide them to said collating pins or devices.
14. In a typewriting machine, the combination with a rotatable platen and paper-apron therefor, of collating pins or devices at the front side of the platen, a collating table adjacent said pins or devices, and means at the adjacent edges of said table, forming a covered guideway for the sheets to be collated, and arranged to positively guide said sheets to a position adjacent said collating pins or devices.
15. In a front-strike writing machine, the combination with a revoluble platen, of a collating table arranged at the delivery side thereof, and leading-edge gages placed at the sides of the collating table, said gages separated to permit the body of the sheet to pass therebetween, and designed to contact with gaging-shoulders formed upon the sheet, and means for moving said gages out of sheet-obstructing position.
16. In a front-strike writing machine, the combination with a revoluble platen, of a collating table arranged at the delivery side thereof, leading-edge gages placed at the sides of the collating table, said gages separated to permit the body of the sheet to pass therebetween, and designed to contact with gaging-shoulders formed upon the sheet, and means overlying said collating table and extending downwardly from said gages to the printing line for guiding the work-sheet thereto.
17. In a front-strike writing machine, the combination with a revoluble platen, of a collating table arranged at the delivery side thereof, leading-edge gages placed at the sides of the collating table, said gages separated to permit the body of the sheet to pass therebetween, and designed to contact with gaging-shoulders formed upon the sheet, and means overlying said collating table and extending downwardly from said gages to the printing line for guiding the work-sheet thereto.
18. In a front-strike writing machine, the combination with a revoluble platen, of a collating table arranged at the delivery side thereof, leading-edge gages placed at the sides of the collating table, said gages separated to permit the body of the sheet to pass therebetween, and designed to contact with gaging-shoulders formed upon the sheet, and means for gaging the side edges of the sheets.
19. In a front-strike writing machine, the combination with a revoluble platen, of a collating table arranged at the delivery side thereof, leading-edge gages placed at the sides of the collating table, said gages separated to permit the body of the sheet to pass therebetween, and designed to contact with gaging-shoulders formed upon the sheet, and a feed roll releasable to permit the introduction of the sheet and in position to press the sheet against the platen while the sheet is in contact with said gages.
20. In a front-strike writing machine, the combination with a revoluble platen, of a collating table at the delivery side of the platen, means for gaging and truing the side edge of the work-sheet, and a leading-edge gage to contact with a shoulder upon the work-sheet, said leading-edge gage mounted at the side of the table to permit the body of the work-sheet to pass the same while trued by means of its side edge.
21. In a front-strike writing machine, the combination with a revoluble platen, of a collating table at the delivery side of the platen, means for gaging and truing the side edge of the work-sheet, a leading-edge gage to contact with a shoulder upon the work-sheet, said leading-edge gage mounted at the side of the table to permit the body of the work-sheet to pass the same while trued by means of its side edge, and an overlying sheet-guide extending from said leading-edge gage toward the printing line upon the platen.
22. In a front-strike writing machine, the combination with a revoluble platen, of a collating table at the delivery side of the platen, means for gaging and truing the

side edge of the work-sheet, a leading-edge gage to contact with a shoulder upon the work-sheet, said leading-edge gage mounted at the side of the table to permit the body 5 of the work-sheet to pass the same while trued by means of its side edge, and means for moving said leading-edge gage out of the path of the advancing sheet.

23. In a front-strike writing machine, the 10 combination with a revoluble platen, of a collating table at the delivery side of the platen, means for gaging and truing the side edge of the work-sheet, a leading-edge gage to contact with a shoulder upon the 15 work-sheet, said leading-edge gage mounted at the side of the table to permit the body of the work-sheet to pass the same while trued by means of its side edge, a feed roll to run upon the under side of the platen, 20 and means connected thereto to release said

feed roll and simultaneously bring said leading-edge gage to working position.

24. In a front-strike writing machine, the combination with a revoluble platen, of a 25 collating table arranged at the delivery side thereof, leading-edge gages placed at the sides of the collating table, said gages separated to permit the body of the sheet to pass therebetween, and designed to contact with gaging-shoulders formed upon the sheet, a 30 feed roll to run upon the under side of the platen, and means connected thereto to release said feed roll and simultaneously bring said leading-edge gages to working position.
